UNITED STATES PATENT OFFICE

CHARLES H. NORTON, OF WORCESTER, MASSACHUSETTS, ASSIGNOR TO NORTON GRINDING COMPANY, OF WORCESTER, MASSACHUSETTS, A CORPORATION OF MASSACHUSETTS.

GRINDING-MACHINE TABLE.

1,235,232.

Specification of Letters Patent. Patented July 31, 1917.

Application filed October 24, 1916. Serial No. 127,386.

To all whom it may concern:

Be it known that I, CHARLES H. NORTON, a citizen of the United States, residing at Worcester, in the county of Worcester and State of Massachusetts, have invented a new and useful Grinding-Machine Table, of which the following is a specification.

This invention relates to a grinding machine table and particularly to improved drainage devices therefor.

I have shown my invention as embodied in a grinding machine table having an upstanding portion extending longitudinally of the table and forming one support for the head and foot stocks, but certain features of my invention may be utilized with other types of table.

It is the object of my invention to provide a construction of grinding machine table in which the water falling thereon from the work or the grinding wheel will be removed therefrom at a plurality of separated points, thereby preventing flow of water along the table.

With this object in view, my invention in its preferred form contemplates the provision of a plurality of separated grooves extending transversely of the table and preferably inclined rearwardly. The grooves may, if so desired, extend beneath the upstanding portion and may be connected to a drain trough extending longitudinally along the front of the table.

My invention further relates to certain arrangements and combinations of parts hereinafter described and more particularly set forth in the appended claims.

A preferred form of my invention is shown in the drawings in which—

Figure 1 is a sectional elevation of a grinding machine table taken along the line 1—1 in Fig. 2, and

Fig. 2 is a partial plan view of the table shown in Fig. 1, drawn on a reduced scale.

Referring to Fig. 1, I have shown a swivel table 10 mounted on a sliding table 11 which is supported on ways 12 and 13 formed on the base 14 of a grinding machine. The swivel table 10 is provided with an upstanding portion 15 having ways 16 thereon, and forming one support of the foot stock 20 and of the head stock (not shown). An additional finished surface 21 forms a second support for the head and foot stocks, the

latter being secured to the table by a clamp- 55 ing member 22 and bolt 23.

The foot stock may be moved longitudinally along the ways 16 and 21 by means of a pinion 24 engaging a rack 25 secured to the upstanding portion 15, a suitable hand 60 wheel 26 being provided for turning the pinion. The work is indicated at K and a portion of the grinding wheel at W. All of the parts thus far described are of the usual form and constitute no part of my invention. 65

Referring to Fig. 2 it will be seen that a plurality of grooves 30 are formed in the upper surface of the table, extending transversely across the same. In the preferred form, these grooves extend beneath the portion 15 and connect with a trough 31 extending along the front edge of the table. The bottom of the grooves are inclined rearwardly and conduct the water received therein to the back of the table, where the 75 water passes downward into a trough 32 formed in the base of the machine.

By this provision of a plurality of separated transverse grooves, the flow of water along the table and particularly beneath the 80 head and foot stocks is prevented. It is impossible for any considerable amount of water to accumulate upon the table as every small portion thereof will be drained away by the adjacent grooves.

While I have shown the grooves as extending completely across the table and beneath the portion 15, many of the advantages of my invention can be realized by providing grooves on the rear portion of the table, only, 90 omitting the passages beneath the portion 15. It is of course obvious that the invention is applicable to a plain grinding machine table as well as to the swivel table shown in the drawings, and that it may be 95 applied to the tables of other machines in which similar conditions are found.

Having thus described my invention it will be evident that changes and modifications can be made therein by those skilled 100 in the art without departing from the spirit and scope of my invention as set forth in the claims, and I do not wish to be otherwise limited to the details herein disclosed, but what I claim is:—

1. A grinding machine table having a plurality of separated transverse drainage passages formed therein to remove water

falling on said table, and to prevent said water flowing longitudinally of said table.

2. A grinding machine table having a plurality of separated transverse drainage passages formed therein, each inclined toward the rear of the table, whereby water falling upon the table will be drained into a trough formed in the base of the machine.
3. A grinding machine table having an upstanding portion extending longitudinally thereof and forming one support for the head

and foot stocks, said table having a trough along its front edge and having a plurality of separated rearwardly-inclined transverse drainage passages formed therein, extending across the table and beneath said upstanding portion and connecting with said trough, whereby water may be effectively removed from said table and trough.

In testimony whereof I have hereunto affixed my signature.

CHARLES H. NORTON.
